MOTOR JACK

William J. Nelson, Oak Park, Ill., assignor to Jay E. Burns, Trustee, Chicago, Ill.

Application February 27, 1939, Serial No. 258,712

5 Claims. (Cl. 254—100)

My invention relates to jacks, more particularly of the type having a motor base, the jack standard being carried by a vertically movable piston adapted to be raised by fluid pressure. Such a device in which the motor piston is repeatedly raised and lowered by supplying and releasing fluid pressure to and from the cylinder space under the piston, whereby to reciprocate the jack standard and load thereon, may be advantageously used for rocking or vibrating an automobile body in relation to its supporting springs to promote effective penetration of grease into the spring joints and shackles and between the leaves of the springs. The present invention provides improvements contributing to practicability, efficiency and convenient utility of an automobile rocker jack or other jack of the motor base type, particularly in the case of a tall sectional jack to be used in a lubricating pit or beneath an automobile supported in an elevated position on a lift or overhead runway.

A feature of the invention is a novel construction for an extensible jack comprising telescoping sections and carrying a jack screw operable by rotation of the upper section of the jack standard, the construction being of practicable and convenient character and enabling the jack to be quickly extended and manipulated for jacking purposes. A further feature is a jack structure of the motor base type embodying in its lower portion separate members having a ball and socket mounting one upon the other, whereby to enable the jack standard to be established in erect position when the device sets on an inclined floor, as on the portion of the floor of a lubricating pit adjacent the central drain of the pit. Among other features is the provision of means to enable the weight of the device to be transferred to rider wheels normally clear of the floor, so as to render the device easily portable and to enable it to be quickly shifted into position for operative use.

One practicable device embodying the invention is shown for illustration in the accompanying drawings, in which:

Fig. 1 is a side elevation of the illustrative device.

Fig. 2 is a sectional plan view taken on the line 2—2 of Fig. 1, looking in the direction of the arrows.

Fig. 3 is an enlarged vertical section through a portion of the illustrative device, taken on the line 3—3 of Fig. 2, looking in the direction of the arrows.

Fig. 4 is a horizontal section through the motor base, taken on the line 4—4 of Fig. 1 and showing the portion of the structure below the line in top plan view.

Fig. 5 is a central vertical section taken on the

line 5—5 of Fig. 4, looking in the direction of the arrows.

Fig. 6 is a view corresponding to Fig. 4 showing a modification with respect to the supporting base of the device.

Fig. 7 is a vertical section taken on the line 7—7 of Fig. 6.

Figs. 8 and 9 are sectional views representing modifications with respect to the manner of mounting the jack standard.

Referring to Figs. 1 to 6, the illustrative device therein shown is an automobile rocking jack comprising a fluid operated motor and a tall extensible jack standard carried by the motor piston. In the drawings, 10 denotes the motor cylinder, 15 closed at its upper and lower ends by the heads 11 and 12; and 13 is the motor piston, whose upwardly extending piston rod 14 is guided in the central sleeve boss 15 of the upper cylinder head. In operation, the piston is raised by fluid pressure thereunder, and lowered by the weight or load thereon as the pressure is relieved through a restricted exhaust passage. Motors of the type for a rocker jack are known to the art. Such motor may be operated by compressed air, being 25 equipped for connection with a source of compressed air and having suitable valve mechanism for controlling admission and exhaust of motive fluid to and from the lower end of the cylinder for causing reciprocation of the piston, preferably 30 at a rate of about from 20 to 30 reciprocations per minute.

Mounted on and affixed to the piston rod as a continuation thereof is the tubular jack post 16 constituting the lower section of an extensible 35 standard whose upper section or strut 17, telescoping in the lower section, is carried by and rotatable with a hand wheel 18 swivelled to the upper end of the lower section. The upper section or strut 17 has an axially bored and internally threaded upper portion 19 engaged by the jack screw 20 on which is non-rotatably mounted the jack head or saddle 21. It may be assumed that the device sets on the floor of a pit beneath an automobile standing thereover, or that the 45 device is mounted beneath an automobile supported in elevated position on a lift or overhead runway, and that the jack is adjusted to bring the saddle 21 into engagement with the central member or one of the end members or side members of the automobile chassis frame, or that the saddle 21 carries thereon a removably mounted top saddle 22 which is brought into engagement with the central members 23 of the type of chassis frame for a Ford car. The hand wheel 18 50 may now be rotated to feed the jack screw upwardly, so as to lift the chassis or supported part thereof in relation to the vehicle springs; and the motor may then be operated to reciprocate the jack structure carried thereby, thus rocking or 55 60

vibrating the chassis or vehicle body in relation to its supporting springs.

In order to permit the jack to be quickly extended and conveniently operated for feeding the jack screw, the jack standard embodies the construction shown in Figs. 2 and 3, wherein the upper section or strut 17 is slidably and non-rotatably fitted in the hub of the hand wheel 18 and is formed or constructed as a ratchet bar engageable by a pawl or pawls carried by the hub of the hand wheel; the arrangement of the ratchets and pawls being such as to permit the jack section or strut 17 to be lifted and held in the position to which it is elevated. In the specific construction shown, the strut 17 below the portion thereof carrying the jack screw is substantially square in cross section but with rounded corners, as shown in Fig. 2, being vertically slidable in a correspondingly formed opening in the hand wheel hub 24, and such rounded corners being slidably or loosely fitted in the tubular jack post 16. The strut 17 is shown having longitudinal ratchets 25 on opposite sides, but the invention contemplates a construction in which the strut 17 has a single 25 ratchet on one side only. The teeth of the ratchets 25 are presented downwardly and engaged by the upper ends of the pawls 26 which are pivotally mounted on pins or pintles 27 between ears 28 on the hand wheel hub. Near their ends 30 in engagement with the ratchet teeth the pawls are supported on shoulders 29 on the hand wheel hub, thus taking the weight from the pawls close to the ratchet bar strut. The hand wheel hub bears rotatably on the cap 30 fastened on the 35 upper end of the jack post 16, said hub being shown formed with a depending flange or skirt portion 31 enclosing said cap and having pins 32 (Fig. 2) engaging an annular groove 33 in said cap to provide a swivel connection for the hand wheel. The ratchet pawls 26 are spring-held in 40 engagement with the ratchet teeth by springs 34 interposed between the skirt portion of the hand wheel hub and tail extensions 35 of the pawls, said tail extensions being formed to provide handles 36. By means of such handles, which extend 45 below the hand wheel, the operator can safely disengage the pawls from the ratchet bar strut 17 after the hand wheel has been operated to feed the jack screw downwardly sufficiently to be relieved of the load.

A device of the class described must sometimes be mounted over a drain in a lubricating pit or on an inclined floor adjacent to or near the drain, in which event, unless the operator goes to the trouble of providing wedges or shims under the 55 motor base, the jack standard will be out of plumb or in a tilted instead of a perpendicular position, so that there will be danger of tilting over the device under the action of the load thereon, particularly in the case of a rocker jack. To obviate this difficulty, and to avoid the necessity of propping up or shimming the motor base to hold the jack standard erect, I have provided a novel motor base structure embodying separate members bearing one upon another and having 60 contacting spherical bearing surfaces, or at least one of said members having a convex surface in bearing contact with the other, with connecting means between the members allowing a limited angling of the upper member relative to the lower member, so that the jack standard can be established in erect position notwithstanding that the motor base rests on an inclined support.

As shown in Figs. 1, 4 and 5, the lower cylinder head 12 is formed with a concave bottom surface 75 which bears on a convex upper surface 40 of a

separate base member 41, said base member having the under side of its central portion spaced from the floor. Said cylinder head and base member are connected by the bolt-screw 42 engaging a tapped hole in the cylinder head and passing through an opening 43 in the base member, the head of the screw or the washer 44 engaging the under side of the base member. Said bolt screw may constitute a drain plug, the tapped hole therefor in the cylinder head being a drain opening. The hole 43 in the base member is of substantially larger diameter than the bolt screw, thereby allowing a limited angling of the motor cylinder relative to the base member, so that the jack standard can be set in erect position when 15 the base member rests on an inclined floor. The screw bolt 42 connects the parts in such manner as to prevent accidental separating of the parts. The rim portion of the base member is formed on its under side with three appropriately spaced 20 flat-bottomed feet 48, of only slight elevation, thus providing a three point support whereby to avoid wobbling if the device sets on an uneven floor surface. A pair of rider wheels are shown at 45, whose axle 46 is mounted in lugs or ears 25 47 projecting laterally from the base member. These wheels are carried by the base member adjacent to one edge thereof and just clear of the floor, so that they do not normally afford a roller support; but by tilting the motor jack toward 30 the rider wheels they are brought into contact with the floor and take the weight of the device, so that it can be readily shifted from one position to another.

In Figs. 6 and 7, showing a modification of the 35 base structure, the lower cylinder head designated by the numeral 116 is formed with a bottom convex bearing member 50 which bears in the upper concave surface of the separate base member 51. In this instance the cylinder head is 40 shown formed with lateral lugs 52, which engage under an overhanging flange 53 on the base member to connect the parts together, said flange having notches 54 to permit insertion of the lugs therethrough. It will be understood that in assembling the structure of Figs. 6 and 7 the parts are held in such relation as to register the lugs 52 with the notches 54, and after the lugs are inserted through the notches the base member and cylinder are turned one relative to the other to 45 engage the lugs under the flange 53. Sufficient clearance is allowed between the lugs and flange to permit limited angling of the motor cylinder and jack standard on the base member.

In Figs. 8 and 9, constructions are shown where- 55 by, instead of mounting the cylinder on a sepa- 60 rate base member, the lower section of the jack standard can be mounted on the motor piston rod in a manner to permit the standard to be held erect when the motor base rests on an inclined supporting surface. In Fig. 8, the numeral 214 designates the motor piston stem or rod, and the numeral 216 designates the jack post or lower section of an extensible jack standard such as already described; these parts typifying sections 65 of the jack structure as a whole, whose adjoining ends are in the lower part of the structure. Fast on the upper end of the lower section or piston rod 214 is a bearing member 60 having a convex bearing surface. Enclosing and rigidly secured to the end portion of the other section or jack post 216 is a sleeve 61 formed therein with a bearing member 62 which bears on the member 60; said sleeve having an extension enclosing the end portion of the section 214, and there being sufficient clearance at 63 between the sleeve and 70 75

section 214 to allow a limited angular movement of the jack standard relative to the piston rod. A connection between the parts is provided by the screw 64, the hole therefor in the member 5 62 being sufficiently large to allow the member 62 to assume different angular positions on the member 60. In lieu of the specific construction of Fig. 8, a reversal thereof may be used.

In Fig. 9, the numeral 314 designates the motor piston rod and 316 denotes the jack post. Their adjoining ends have the contacting bearing members 70 and 71, one or both of which may have a convex bearing surface. A sleeve 72 encloses the adjoining end portions of the jack sections 314 and 316, said sleeve being connected with said sections by the pins 73. Clearance is provided between the sleeve and jack sections, and in the pin holes in the sections, allowing limited relative angling.

20 It will be observed that the constructions of Figs. 4 and 5 and those of Figs. 6 to 9 exemplify different specific constructions in a jack embodying in its lower portion separate members one of which is mounted directly on the other, the lower 25 of said members having an upwardly facing bearing surface and the upper of said members having a bottom bearing surface bearing on said first mentioned surface, at least one of said surfaces being convex to permit the upper of said 30 members to assume different angular positions relative to the lower of said members, whereby the principal portion of the structure above said contacting bearing surfaces can be established in erect position when the base of the structure 35 rests on an inclined supporting surface, and connecting means between said members allowing a limited angling movement of the upper of said members relative to the lower of said members. The members here referred to are the cylinder and separate base member in Figs. 4 and 5, the members 60 and 62 in Fig. 8, and 70 and 71 in Fig. 9.

The term "motor jack" is intended to apply either to an automobile rocking jack or one 45 whose motor piston reciprocates the jack standard with the load thereon or to one whose motor operates to raise the jack standard with its supported load by fluid pressure and to sustain it in raised position until release of the fluid pressure 50 at the will of the operator.

Embodiments of the invention in such modified forms as may be within the scope of the following claims are intended to be secured.

I claim as my invention:

55 1. A motor jack having telescoping jack sections, the upper section being slidable and rotatable in the lower section, a hand wheel rotatably mounted on the upper end of the lower section, the upper section having a longitudinal ratchet and being slidably but non-rotatably fitted in the hub of said hand wheel, whereby rotation of the hand wheel will rotate the upper section through direct driving engagement therewith, pawl means carried by said hub coacting with said ratchet, said ratchet and pawl means being arranged to permit lifting the upper section in said hub and to support it in the position to which it is elevated, and an axially arranged jack screw in threaded engagement with the upper section, said screw adapted to be fed by rotation of said upper section by said hand wheel.

2. A motor jack having telescoping jack sec-

tions, the upper section being slidable and rotatable in the lower section, a hand wheel rotatably mounted on the upper end of the lower section, the upper section having a longitudinal ratchet and being slidably but non-rotatably fitted in the hub of said hand wheel, whereby rotation of the hand wheel will rotate the upper section through direct driving engagement therewith, a pawl mounted in said hub and spring pressed in engagement with said ratchet, said ratchet and 10 pawl being arranged to permit lifting the upper section in said hub and to support it in the position to which it is elevated, said hub having a portion adjacent to the ratchet on which the pawl rests when supporting said upper section, 15 and an axially arranged jack screw in threaded engagement with the upper section, said screw adapted to be fed by rotation of said upper section by said hand wheel.

3. A motor jack having telescoping jack sections, the upper section being slidable and rotatable in the lower section, a hand wheel rotatably mounted on the upper end of the lower section, the upper section having a longitudinal ratchet and being slidably but non-rotatably fitted in the hub of said hand wheel, whereby rotation of the hand wheel will rotate the upper section through direct driving engagement therewith, a pawl mounted in said hub and spring pressed in engagement with said ratchet, said ratchet and 20 pawl being arranged to permit lifting the upper section in said hub and to support it in the position to which it is elevated, said hub having a portion adjacent to the ratchet on which the pawl rests when supporting said upper section, 25 and an axially arranged jack screw in threaded engagement with the upper section, said pawl having a depending tail portion providing a downwardly extending lever handle under said wheel by which to operate the pawl to disengage 30 it from the ratchet, said screw adapted to be fed by rotation of said upper section by said hand wheel.

4. A jack including vertically disposed sections in end to end relation and whose adjoining ends 45 are in the lower part of the structure, a sleeve rigid with and enclosing the end portion of one of said sections and extending therefrom and loosely enclosing the end portion of the other section, said other section having a bearing member on its end, said sleeve having an internal bearing member between its own ends and between the ends of said sections, said members bearing one on the other and having contacting spherical surfaces, there being sufficient clearance between said sleeve and said section which has a bearing member on its end to allow a limited angling of one section relative to the other, and connecting means between said sections allowing such limiting angling.

5. A jack embodying vertically disposed sections in end to end relation and whose adjoining ends are in the lower part of the structure, said sections having bearing members on said ends, one bearing directly on the other, at least one 65 of said members having a convex bearing surface, a sleeve loosely enclosing the end portions of said sections, and pins transfixing said sleeve and sections, each pin being loose in one of the elements with which it is connected.
